To all whom it may concern:

Be it known that I, OLIVER CABANA, Jr., a citizen of the United States, residing at Buffalo, in the county of Erie and State of New York, have invented and produced a new and original Design for a Supporting Member for Bath-Seats, of which the following is a specification, reference being had to the accompanying drawing, forming part thereof.

As shown in the drawing, the leading or material feature of my design consists of an arm of a continuous rod, forming a skeleton having a portion *a*, in which the sides are parallel, and from the outer part of *a* the arm

extends upward, inclines outward, and diverges laterally at *b b*, and the ends *c c* of the arm engage a horizontal bar *d*.

Having described my invention, what I claim as new, and desire to secure as Letters Patent, is—

The design for a supporting member for bath-seats, substantially as herein shown and described.
